UNITED STATES PATENT OFFICE.

CHARLES O. HELD, OF COLUMBUS, OHIO.

DESIGN FOR A PICTURE-FRAME.

SPECIFICATION forming part of Design No. 21,293, dated January 12, 1892.

Application filed October 8, 1891. Serial No. 408,162. Term of patent 3½ years.

To all whom it may concern:

Be it known that I, CHARLES O. HELD, a citizen of the United States, residing at Columbus, in the county of Franklin and State of Ohio, have invented and produced a new and original Design for Picture Frames or Supports, of which the following is a specification, reference being had to the accompanying drawings, forming part thereof.

10 Figure 1 is a face view of my newly-designed picture frame or support; and Fig. 2 is a sectional view on line $x-x$ of Fig. 1, these two views being deemed necessary to fully illustrate my design.

15 The leading features of my design consist in a guitar-shaped frame having a raised or beaded edge and oval openings in the body of said frame having puffed and beveled linings and an ornamental bead surrounding each of said openings.

a represents the body of the frame or support, which, as shown, has the form and outline of a guitar.

b represents the two oval openings in said

guitar-body, each of which is oblique to the central longitudinal line of the body and is provided with a puffed and beveled ornamental lining *c*. The face of the frame-body *a* is provided adjoining its edges with a bead *d*, which projects beyond the surface of the body *a*.

d represents ornamental bead projections which surround each of the openings *b*.

The body *a* has an extension in the form of a guitar-neck or finger-board *f*, and upon said body and finger-board are made to appear ornamental representations of guitar-strings *f'*, which are crossed on said finger-board by representations of frets *f''*.

What I claim, and desire to secure by Letters Patent, is—

The design for a picture frame or support, as herein shown and described.

CHARLES O. HELD.

In presence of—
C. C. SHEPHERD,
THOS. S. GATES.
